 P. R. Mallory & Co., Inc., Indianapolis, Ind., a
 corporation of Delaware

Application February 2, 1938, Serial No. 188,245

6 Claims. (Cl. 175—365)

This invention relates to electromagnetic vibratory interrupter circuits.

An object of the invention is to improve the vibrator circuits.

5 Other objects of the invention will be apparent from the following description and accompanying drawing taken in connection with the appended claims.

The invention comprises the features of construction, combination of elements, arrangement of parts, and methods of manufacture and operation referred to above or which will be brought out and exemplified in the disclosure hereinafter set forth, including the illustrations in the 15 drawing.

The figure of the drawing shows a vibrator circuit embodying features of the present invention.

While a preferred embodiment of the invention is described herein, it is contemplated that considerable variation may be made in the method of procedure and the construction of parts without departing from the spirit of the invention. In the following description and in 25 the claims, parts will be identified by specific names for convenience, but they are intended to be as generic in their application to similar parts as the art will permit.

Referring to the drawing a vibrator circuit is 30 shown utilizing a vibrator of the type comprising a vibratory reed having an armature 30, a tongue carrying contact 33 and a pair of side arms carrying contacts 37 and 38 respectively. The reed is vibrated by an electromagnet having 35 a core 22 and a pair of windings 52 and 53, the end of the magnet core 22 being disposed adjacent armature 30 of the reed. The mechanical structure of the vibrator may be of any type well-known in the art. The vibrator has associated 40 with it in the circuit a battery 54 or other source of low voltage D. C. power and a transformer having a center tapped primary winding 55 and a secondary winding 56 of any suitable type. The two ends of primary winding 55 are connected 45 to relatively stationary contacts 39 and 40 respectively which co-operate with reed-supported contacts 37 and 38 respectively. One terminal of battery 54 is connected to the reed and the other terminal to the mid-point of primary winding 55. Electromagnet winding 52 is connected 50 at one end to the terminal of battery 54 which is also connected to the mid-point of primary winding 55. The corresponding end of magnet winding 53 is connected to the vibrator reed. The opposite ends of windings 52 and 53

are both connected to a relatively stationary contact 34 which co-operates with reed-supported contact 33. If desired, the reed may be grounded as shown.

At the start of the cycle of vibration the winding 53 has its ends short circuited by contacts 33, 34. Winding 52, however, is connected to battery 54 and to ground through contacts 33, 34, thus magnetically attracting the reed. When contacts 33, 34 are opened by the swing of the 10 reed this establishes winding 53 in series with winding 52 and battery 54. A discharge path for the energy of winding 52 is thereby provided through winding 53 so that no arcing can take place across contacts 33, 34. Winding 53, when 15 connected in this circuit, has an opposite magnetizing effect on core 22 so that the electromagnet will be demagnetized.

While the present invention, as to its objects and advantages, has been described herein as 20 carried out in specific embodiments thereof, it is not desired to be limited thereby but it is intended to cover the invention broadly within the spirit and scope of the appended claims.

What is claimed is:

1. A vibrator system comprising a vibratory switch arm and an electromagnet for vibrating said arm, a pair of windings on said electromagnet, one end of said windings being joined together, a source of electric current, the unjoined ends of said windings being connected respectively to the opposite terminals of said current source, said switch arm connecting the joined ends of said windings to one terminal of said current source in the unattracted position of 30 said arm and opening said connection in the attracted position of said arm. 35

2. An electromagnetic vibratory interrupter system comprising an electromagnet, a first contact, a vibratory contact cooperating therewith, a current source, said contacts connecting the winding of said electromagnet in series with said current source when said contacts are in engagement, said electromagnet effecting vibration of said vibratory contact to open and close said 40 contacts, and a second winding for said electromagnet connected in shunt with said contacts. 45

3. An electromagnetic vibratory interrupter system comprising an electromagnet, a first contact, a vibratory contact cooperating therewith, a current source, said contacts connecting the winding of said electromagnet in series with said current source when said contacts are in engagement, said electromagnet effecting vibration of 50 said vibratory contact to open and close said contacts. 55

tacts, and a second winding for said electromagnet connected in shunt with said contacts, said second winding having an opposite polarity magnetizing effect on said electromagnet from the 5 first winding.

4. An electromagnetic vibratory interrupter system comprising an electromagnet, a first contact, a vibratory contact co-operating therewith, a current source, said contacts connecting the 10 winding of said electromagnet in series with said current source when said contacts are in engagement, said electromagnet effecting vibration of said vibratory contact to open and close said contacts, and a second winding for said electromagnet connected in shunt with said contacts, a transformer having a center tapped primary winding, and contact means vibrated by said electromagnet to connect said current source alternately in series with the two halves of said 15 primary winding.

5. An electromagnetic vibratory interrupter system comprising an electromagnet, a first contact, a vibratory contact co-operating therewith, a current source, said contacts connecting the 20 winding of said electromagnet in series with said current source when said contacts are in en-

gagement, said electromagnet effecting vibration of said vibratory contact to open and close said contacts, and a second winding for said electromagnet connected in shunt with said contacts, a transformer, and contact means vibrated by 5 said electromagnet to connect said current source alternately in opposite polarity directions through the primary winding of said transformer.

6. An electromagnetic vibratory interrupter system comprising an electromagnet having a 10 pair of windings of opposing polarity, a vibratory reed controlled thereby, a plurality of contacts mounted on said reed and relatively stationary contacts co-operating therewith, a current source, a transformer having a center-tapped primary 15 winding, one pair of said co-operating contacts being closed in the normal rest position of said reed, said contact pair connecting said current source to a first of said electromagnet windings, the second of said windings being connected in 20 shunt with said contact pair, and other of said contact pairs connecting said current source alternately to the two halves of said transformer primary winding during vibration of said reed.
